UNITED STATES PATENT OFFICE.

WALTER ROWBOTHAM, OF MONTREAL, QUEBEC, CANADA.

APPARATUS FOR CLEANING CARPETS AND LIKE FABRICS.

1,007,800.

Specification of Letters Patent.

Patented Nov. 7, 1911.

Application filed December 21, 1908. Serial No. 468,669.

To all whom it may concern:

Be it known that I, WALTER ROWBOTHAM, of the city of Montreal, in the Province of Quebec and Dominion of Canada, have invented certain new and useful Improvements in Apparatus for Cleaning Carpets and Like Fabrics, and do hereby declare that the following is a full, clear, and exact description of same.

10 This invention relates to a device for cleaning carpets and similar fabrics and is an improvement on the construction disclosed in my former application Ser. No. 389,759, filed August 23rd, 1907, and the 15 object is to provide means for thoroughly cleaning carpets and the like which will remove dust and other substances therefrom without injuring the pile of the fabric.

A further object is to provide a sweeper 20 that will operate in corners and close to the walls of a room and that will remove threads and similar substances from the carpet by means of a vacuum created within the machine, acting in conjunction with a brush 25 which loosens particles of dust and threads which the vacuum alone is not able to remove.

A still further object is to provide means for collecting all the matter removed from 30 the fabric within the machine, thereby preventing the escape of same into the surrounding air.

The apparatus consists essentially of a fan or blower driven from the wheels upon 35 which the device runs, said fan being adapted to force a jet of air downwardly upon the carpet for the purpose of stirring up the dust within the same and then to draw said dust or like substances by suction into a suitable receptacle adapted to contain the same. A small brush is provided for removing 40 threads or similar articles which adhere to the pile of the fabric too closely to be removed by the air jet.

45 In the drawings which illustrate my invention:—Figure 1 is a side elevation of the apparatus. Fig. 2 is a vertical longitudinal section of the same. Fig. 3 is a partial side elevation partly in section to show an 50 alternative construction. Fig. 4 is a bottom plan view of the brush. Fig. 5 is a side view of one of the wheel carrying arms. Fig. 6 is an edge view of the same. Fig. 7 is a horizontal section on the line $\alpha-\alpha$ of Fig. 2. 55 Referring to the parts, 7 designates a fan chamber within which the side plates 8 of

the fan are mounted on the shaft 9 by means of the pins 10. The side plates are connected by blades 11 curved as shown in Fig. 2 in order that the fan may more readily take 60 in air at the center and deliver it under slight pressure from the periphery into the space 7^a. The air escapes from the space 7^a through the rearwardly and downwardly projecting nozzle 12, thus stirring up the 65 dust in the fabric to be cleaned and creating a suction of external air into the space 13, which opens directly into the dust conduit 14. A brush 15 having widely separated bristle tufts is located across the mouth of 70 the dust conduit 14. The purpose of this brush is to draw threads or other similar matter which the air jet is unable to discharge and roll the same up so that they may be readily carried into the dust conduit 75 between the tufts of bristles by the air current. The dust laden air, after traversing the conduit 14, emerges from the mouth 16 thereof into the dust receiver 17 and impinges on a curved deflecting plate 18 which 80 directs it downwardly. The air now passes through a screen 19 hanging from the deflecting plate 18. The vibrations of this screen caused by the movement of the apparatus back and forth, serve to dislodge any 85 particles of dust which would adhere to the screen and clog the same. After passing through the screen 19, the air passes upwardly through the perforated rear portion 20 of the deflecting plate 18, and through a 90 second screen 21, which removes any dust which may be still carried by the air before the same enters the air passages 22 which lead to the center of the fan chamber 7. The fan is driven by means of pulleys 23 of 95 rubber or other suitable material which frictionally engage the inner face of the wheel rims 24. The wheels are provided with rubber tires 25 which engage the carpet or fabric to be cleaned and insure the wheels 100 against slipping. The wheels are mounted on posts 26 carried on the upper end of levers 27 pivotally mounted on a shaft 28 which extends through the dust receiver. A fork member 29 is pivoted to the lower ends 105 of the levers 27 at 30 and is provided with a suitable socket 31 for the reception of a handle. From the pivot 30, the arms of the fork extend forwardly and upwardly and are provided with hooks 32 adapted to engage the fan shaft 9 to support the weight 110 of the sweeper when the same is being lifted.

or carried; as shown in Fig. 1. Stops 33 are fixed to the sides of the dust receiver to limit the rearward movement of the levers 27. The dust receiver is provided with a cover 34 secured thereto by a resilient packing ring 35 which prevents the escape of dust, and a handle 36 for convenience in withdrawing the cover. The bottom and sides of the cover extend inwardly to form a dust pan 37 on which the dust is deposited from the deflecting plate and screens, and by means of which the dust may be readily removed from the receiver. A guard 38, of rubber or other suitable material, is secured to the front of the machine to prevent damage to furniture, etc.

In the alternative form shown in Fig. 3, I have shown a small rotary brush 39 replacing the fixed brush 15. This brush is driven by means of an elastic belt 40 running over a pulley 41 secured to one of the running wheels. It is obvious that any suitable mechanism may be substituted for the elastic belt.

The operation of the device will be readily understood from the foregoing description and consists, briefly, in forcing a jet of air downwardly and rearwardly on to the fabric to be cleaned. This jet of air, in conjunction with the brush 15, stirs up the dust in the fabric which is carried through the brush and up the conduit 14 by the air current, into the dust receiver 17. The dust and air are here separated, the air being returned to the fan chamber through the air passages 22 to be again directed on to the fabric. The direction and velocity of the jet drawn in through the air inlet 13 furnishes sufficient air supply to make up for any loss of air which may have occurred during the cycle of operation.

Having thus described my invention, what I claim is:—

1. A device of the class described comprising a dust receiver, a blower, levers pivoted to the dust receiver intermediate their extremities, a pair of running wheels pivoted to the upper extremities of said levers, a driving fork uniting the lower extremities of said levers, an air nozzle, at the front of the blower adapted to direct a jet of air downwardly on to the fabric to be cleaned, a brush at the rear of said nozzle, and a conduit leading from the rear of the brush to said dust receiver.

2. A device of the class described comprising a dust receiver, a blower, an air nozzle at the front of the blower adapted to direct a jet of air downwardly onto the fabric to be cleaned, levers pivoted to the dust receiver intermediate their extremities,

running wheels revolubly mounted at the upper extremities of said levers, a driving fork uniting the lower extremities of said levers, and means for driving the blower 65 from the wheel rims.

3. A device of the class described comprising a dust receiver, a blower, an air nozzle at the front of the blower adapted to direct a jet of air downwardly onto the 70 fabric to be cleaned, levers pivoted to the dust receiver intermediate their extremities, running wheels revolubly mounted at the upper extremities of said levers, means for connecting the blower and driving wheels, 75 a driving fork uniting the lower extremities of the levers, whereby the wheels are thrown into gear with the blower when the apparatus moves in a forward direction and out of gear when the apparatus moves in a reverse direction, substantially as described.

4. A carpet cleaning device comprising a fan chamber, a revoluble fan therein, an air nozzle at the front of said fan chamber adapted to direct a jet of air downwardly 85 and rearwardly onto the fabric to be cleaned, a shaft for said fan, a dust receiver at the rear of the fan chamber, levers pivoted to said dust receiver, running wheels mounted on the upper extremities of said levers, a 90 fork pivoted to the lower extremities of said levers, a handle socket fixed to said fork, pulleys mounted on the fan shaft and frictionally engaging the inner faces of the wheel rims.

5. A carpet cleaning device comprising a fan chamber, a revoluble fan therein, a shaft for said fan, a dust receiver, at the rear of said fan chamber, levers pivoted to the dust receiver intermediate their extremities, running wheels revolubly mounted at the upper extremities of said levers having inwardly projecting rims, a fork member pivoted to the lower extremities of said levers, a handle socket fixed thereto, and pulleys carried 105 by the fan shaft adapted to frictionally engage the inner face of the wheel rims, substantially as described.

6. A carpet cleaning device comprising a pair of running wheels, a fan or blower, driving pulleys therefor, a dust receiver, an inlet conduit for said receiver, levers pivoted to the dust receiver carrying said running wheels, and a driving fork operating said levers to throw the running wheels into 110 engagement with the fan pulleys.

In witness whereof I have hereunto set my hand in the presence of two witnesses.

WALTER ROWBOTHAM.
